UNITED STATES PATENT OFFICE

153,396

DESIGN FOR A CAN PERFORATOR

Edward G. Roytek, Mishawaka, Ind.

Application April 28, 1947, Serial No. 138,652

Term of patent 14 years

(Cl. D22—2)

To all whom it may concern:

Be it known that Edward G. Roytek, a citizen of the United States, residing at Mishawaka, in the county of St. Joseph, State of Indiana, have invented a new, original, and ornamental Design for a Can Perforator, of which the following is a specification, reference being had to the accompanying drawing, forming part thereof.

Fig. 1 is a top plan view of a can perforator, showing my new design.

Fig. 2 is a view of the device in side elevation.

Fig. 3 is a view of the device in end elevation.

Fig. 4 is a transverse sectional view of the device taken on line 4—4 of Fig. 1.

Fig. 5 is a transverse sectional view of the top of the device taken on line 5—5 of Fig. 1.

I claim:

The ornamental design for a can perforator, as shown.

EDWARD G. ROYTEK.
